UNITED STATES PATENT OFFICE.

JOHN C. BLEVNEY, OF NEWARK, NEW JERSEY.

TRANSMITTING DEVICE FOR HORSELESS CARRIAGES.

SPECIFICATION forming part of Letters Patent No. 643,627, dated February 20, 1900.

Application filed May 10, 1899. Serial No. 716,212. (No model.)

To all whom it may concern:

Be it known that I, JOHN C. BLEVNEY, a citizen of the United States, residing at Newark, in the county of Essex and State of New Jersey, have invented certain new and useful Improvements in Power-Transmitting Devices for Horseless Carriages; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

The objects of this invention are to reduce the cost of construction, to secure a more simple and compact structure, to permit a free vibration of the carriage-body upon the springs interposed between said body and the axle of the wheels without interfering with the regular movements of the motor and the power-transmitting parts, to reduce the noise produced by operation of the parts, to reduce the amount of vibration in the vehicle due to rapid reciprocation of parts, to secure either a forward or backward movement of the vehicle while employing a belt which operates constantly in one direction, and to secure other advantages and results, some of which may be referred to hereinafter in connection with the description of the working parts.

The invention consists in the improved power-transmitting device for horseless carriages, &c., and in the arrangements and combinations of parts of the same, all substantially as will be hereinafter set forth, and finally embraced in the clauses of the claim.

Referring to the accompanying drawings, in which like letters and figures of reference indicate corresponding parts in each of the several views, Figure 1 is a side elevation of the improved device. Fig. 2 is a detail elevation of certain vehicle reversing and stopping devices. Fig. 3 is a detail section of a speed-varying sprocket-wheel and its threaded shaft. Fig. 4 is a detail side elevation of a sprocket-wheel arranged on the same said shaft and adapted to operate in connection with the reversing and stopping means. Fig. 5 is a section on line x , Fig. 1, looking in the direction of the arrow on the said section-line. Figs.

6 and 7 are detail views of a certain oscillating crank or lever shaft adapted to be reciprocated by the motor-piston. Fig. 8 is a detail view of parts of a belt-clutch adapted to be employed in connection with said oscillating crank-shaft to operate the belt. Fig. 9 is a side view of the clutching devices on line x' , Fig. 8. Fig. 10 is an enlarged detail illustrating the construction of a pair of reversing-clutches in connection with a pair of pulleys over which the belt before referred to is arranged. Fig. 11 is a section of the same on line x^2 . Fig. 12 illustrates in side elevation a center portion of certain clutch-plates and a sleeve inserted between said clutch-plates employed in connection with the clutches. Fig. 13 is a section of the same, said parts taken at line x^3 . Fig. 14 is a sectional detail showing more fully the threaded shaft for operating the reversing-clutch and speed-varying means, showing the relation of the sprocket-wheels before referred to to one another. Fig. 15 is a sectional detail showing the connection of said shaft with a swinging frame carrying the power-transmitting devices, the section of this figure and also of Fig. 14 being taken at line x^4 of Fig. 1. Fig. 16 is a sectional detail of a clutch, taken at line x^5 , Fig. 1; and Fig. 17 is a detail section taken at line x^6 , Fig. 1, showing more clearly the relation of certain power-pulleys, clutching means, and sprocket-wheel from which power is transmitted to the axle.

In said drawings, a , Figs. 1 and 5, indicates the body or frame of a vehicle or carriage, which may be of any suitable construction.

b is the vehicle-wheel, c the axle of said wheel, and d the springs, interposed between the axle and body of the vehicle, the said body thus having a free vibration, either vertical or horizontal, as permitted by said springs.

e indicates the motor, which is seated and secured upon the body of the wagon or carriage and is free to oscillate thereon in any direction with said body, and f indicates the swinging frame carrying the power-transmitting devices, said frame being also supported upon said body and free to move therewith in any direction that the springs d will permit and also movable independent of said body, as will be hereinafter fully described.

Upon or in the said frame *f* are arranged certain pulleys and clutching mechanisms adapted to operate in connection with a flexible belt for transmitting power.

- 5 The motor *e* may be of any ordinary construction and may be adapted to utilize steam, explosive or combustible gas, electricity, liquid air, or any other source of motive power. In connection with the piston (not shown) of the said motor is a crank or lever shaft *h*, the arm *h'* of which extends into engagement with the said piston, and the pivotal part *h⁶* of said shaft *h* is suitably arranged in boxes *h²*, bolted or fastened upon the body of the carriage. At 15 one end of said lever or crank shaft *h* the same is provided with an arm *h³* at right angles to the pivotal part, which arm *h³* is preferably provided with a slot *h⁴*, as shown in Figs. 1 and 6. This arm *h³* is preferably connected to the pivotal part of the shaft *h* by a U-shaped connection *h⁵*, which permits a certain gripping device to be brought closely in line with the axis of pivotal parts of the shaft-body *h* under conditions hereinafter 25 more fully described. Said slotted arm *h³* extends to a point between the side plates *f'* of the frame *f*, and preferably lies at a point midway between the said side plates *f' f'*, where it has a rapid reciprocating action due 30 to the oscillation of the shaft under the power of the motor-piston. The distance of the reciprocal action increases with the distance of the arm from the axial center of the said shaft, as will be apparent. Between the said side plates *f'* is arranged a series of pulleys. At 35 the top of the frame, upon the shaft *i*, is arranged a pair of loose pulleys *j j*. At the lower end of the frame is arranged on the shaft *g* a pair of clutch-pulleys *k k* of larger diameter, 40 and contiguous to the pulleys *j j* and *k k* are loose idle end pulleys *m n*.
- o* indicates an endless strap or belt, preferably of leather, which is turned over the idle end pulleys *m* and *n* and extends downward, 45 one part parallel with another, over the pulleys *j j* and *k k*, the belt parts, where they lie side by side at points between said pulleys *j j* and *k k*, traveling in opposite directions, as will be understood. The oppositely-moving 50 parts of the said belt between said pulleys *j j* and *k k* lie a little apart one part from another—say two inches, more or less—and in the open space between is arranged the reciprocating slotted arm *h³* for operating a double 55 clutch and by means of said clutch the endless belt. The said clutch comprises a frame or frames consisting of a shaft *p*, which may have an antifriction-roller *p¹⁰*, Fig. 8, adapted to lie in the slot *h⁴* of the oscillating arm *h³*. Said shaft *p* has arms or plates *p' p' p' p'* extending from said shaft or bar *p*, and at their upper end said arms or plates are provided with a shaft *p²*, upon which are arranged rollers to engage the back of the belt. 60 Near to the shaft *p²* and parallel therewith are shafts *p³*, supported by the arms *p'*, on which shafts *p³* are arranged eccentric dogs

r r, each having a series of teeth or ruffles, the eccentric projections *r'* pointing oppositely. The said rollers *q* and eccentric dogs *r* are in pairs, as shown in Fig. 6, a roller and a dog being arranged at opposite sides of the oscillating arm and engaging the opposite sides of the strap or belt and imparting motion thereto. The dogs being arranged oppositely, when reciprocated by the slotted arm alternately engage the oppositely-moving parts of the belt to effect the desired continuity of action of the latter in one direction. When the slotted oscillating arm *h³* causes 80 the frame and its dogs *r* to move therewith in one direction, one of the said dogs clutches one of the moving belt portions and imparts power and motion thereto. In the return movement of the slotted reciprocating arm 85 the opposite dog *r* clutches the oppositely-moving belt portion and imparts motion thereto in the opposite direction, so that each movement of the reciprocating arm imparts movement to the belt, which helps in securing uniform or even movement of said belt.

The clutch-frame moving back and forth with the reciprocating arm *h³* may be guided in its movements by ribs or slideways *s*, formed on the inner sides of the side plates *f'* of the frame. While I prefer to employ said guides, and thereby secure a more positive and regular movement of the clutching-frame, I may under some conditions dispense with said guides, the belt itself serving as a 100 guide for the reciprocating clutching devices.

The centrifugal force due to the action of the oscillating arm *h³* or the guides *s* causes the rollers *q* to press constantly against the back of the belt *s*, and the clutching-dogs 105 being eccentrically disposed with reference to their axes act automatically to clutch the belts in one direction of movement and to release automatically from said belt when moving in the opposite direction.

The dogs *r* are caused to clutch the belt more quickly by means of springs, which tend to hold the cam or eccentric projections of the dogs in engagement with the belt, so that they will be quick to bite the belt when in 115 proper movement to do so.

It may be noted that by the construction shown the gripping-dogs *r* will not grip the belt *o* unless the speed of the dog equals the speed of the belt. Should the movement of the belt be greater than that of the reciprocating dog there will be no clutching action, as will be evident. It may be evident that there is a certain amount of independence of action between the movement of the belt and the movement of the reciprocating grip, and thus when the wagon is going at a high rate of speed and the belt also I can, when necessary, retard the propulsive action of the grip and its connections without interfering materially with the movement of the belt.

To vary the speed of the vehicle, I have pivoted the swinging frame *f*, as at *g*, upon links or pendulous connecting-rods *g'*, and in con-

nection with said frame I have provided adjusting mechanism adapted to be controlled by the motorman or driver of the vehicle. In this connection I employ a connecting-rod *t*, which is adapted to be either rotated axially to operate certain reversing-clutches or move longitudinally to turn the frame *f* on its pivots *g* or swing the same on the pendulous rods *g'*. In securing the swinging movement the said rod *t* engages a cross-head *t'*, (shown in Fig. 15,) the said cross-head being provided with an eye to receive said connecting-rod and the said connecting-rod *t* being held in said eye by a head *t²* and a cam or eccentric collar *t³*. The opposite ends of the cross-bar *t'* are pivotally inserted in hollow lugs or boxes *f²*, formed on the inner sides of the side plates *f'* eccentric to the pivot *g*. By this arrangement of parts when the connecting-rod *t* is moved longitudinally it will cause a movement of the frame *f* back or forth therewith, and this movement of the frame changes the relation of the belt-clutch to the slotted arm *h³*, so that the said clutch is brought nearer to or farther from the center of oscillatory movement of said slotted arm *h³*, whereby the distance of reciprocation of the clutch with said arm will be increased or diminished and the speed of the belt and the vehicle driven by connections with said belt will be varied accordingly. Should the clutch-shaft *p* be brought into alinement with the axial portion *h⁶* of the crank-shaft, the said oscillatory movement will be reduced to zero and the vehicle stopped, as will be understood. Thus by means of the said rod *t* and the means employed for operating the same longitudinally I may vary the speed of the vehicle from nothing up to the highest speed permitted by law or the desire of the driver within the capacity of the vehicle and driving mechanism. To operate the connecting-rod *t* longitudinally to swing the frame, I have provided the same at one end with screw-threads *t'*, Fig. 1, and on the threaded part I have arranged a threaded sprocket-wheel *t⁵*, arranged in suitable bearings *t⁶* upon the vehicle and engaged by a chain *t'*, which extends to any point convenient for operation, where it preferably passes over a second sprocket-wheel *t⁸*, operated by a hand-wheel *t⁹* or other suitable means in any desirable manner. The same connecting-rod *t* is employed for reversing the movement of the vehicle and stopping the same and carries at its end within the frame *f* the cam or eccentric *t³*, above referred to, adapted to operate a clutch-shifting lever *u*. The said lever *u* is provided with prongs *u'*, between which the said cam or eccentric *t³* is arranged, as shown in Fig. 11, and is fulcrumed upon suitable cross-bars *u²* of the frame extending from side plate to side plate. In line with the forked end of the lever is pivoted upon suitable fingers or projecting bearings *u⁴* thereof rollers *u³ u⁵*, which are caused to oscillate with the forked end *u'*. When the eccentric *t³* is turned by the shaft

t, the said rollers *u³* inserted between the clutch-plates *v* throw the said plates sidewise toward or from the pulleys *k k*.

To effect a clutching of one or the other of the belt-pulleys *k k* with the sprocket-wheel *y* for transmitting power to the axle of the vehicle, the plates *v v* are coupled or connected, so as to work laterally together under the action of the wheels *u³*, above referred to. The coupling or connecting means preferred comprises a collar *w*, arranged around the hub *y'* of the sprocket-wheel *y*, the said collar *w* being slotted, notched, or recessed to receive the spokes *y²* and permit a movement of said collar in the line of the axis of said collar in connection with the plates *v*. The collar at opposite ends is provided with clutching-teeth *w'*, which extend through notches or openings in the plates *v*, through which said projections extend to enter into clutching relation to the teeth *k'* formed at the inner sides of the hubs of the pulleys *k*. The said plates *v* are also centrally perforated to receive the hub of the sprocket-wheel *y* and permit the lateral movement of the plates *v*. At the opposite sides of the sprocket-wheels *y* are or may be interposed collars or washers *z* between the hub of the sprocket-wheel *y* and the hub of the pulleys *k* to hold the sprocket-wheel and said pulleys in proper relative position. These, of course, may be dispensed with by increasing the length of the hubs and the said pulleys *k k*.

To hold the frame *f* suspended from the body *a* of the vehicle, I have provided links *g'*, which extend upward from the shaft *g* to the brackets or boxes *4*, the said links *g'* being suitably pivoted upon said brackets, so that the said frame *f* is permitted to swing upon the said body *a* of the vehicle, the swinging action being induced by the swinging or vibrating of the vehicle upon the springs *d* and the rod *8*. Power is transmitted from the sprocket-wheel *y* to the axle *c* or a sprocket-wheel *6*, arranged on said axle, by means of a chain belt *7*, the said chain belt being held in operative relation to the sprocket-wheels *y* and *6* by means of the rod *8*, which extends from said axle *c* to the shaft *g*.

To operate the clutches by means of which reverse movement is secured, I have provided means controlled by the operator for turning the shaft *t* in its bearings and the cam or eccentric *t³* in the fork of the lever *u*. The means preferred are shown in Fig. 1, where 9 indicates a sprocket-wheel arranged on the said shaft *t*, preferably on the side of the bearing *t⁶* opposite that having the sprocket-wheel *t⁵*. Said sprocket-wheel 9 permits of the longitudinal movement of the shaft *t* therein, but is provided interiorly with a spline 90, Fig. 14, adapted to enter a longitudinal groove 10 in the shaft. The said sprocket-wheel 9 receives a chain belt 11, which receives its movement from a sprocket-wheel 12, arranged on bearings at a point convenient to be operated by the driver, said

sprocket-wheel 12 being provided with a hand-crank 13, by means of which said sprocket-wheel may be turned on its shaft to effect the desired movement. Contiguous to said hand-crank is a dial 14, having stop-holes 15 adapted to receive a sliding stop-pin 16 of the hand-crank, the said pin being arranged in a cylindrical extension of the crank and being provided with a handpiece 17.

10 The wheels *k* are preferably provided with heavy rims to serve as fly-wheels and to secure regular movement.

In operation the motorman or driver simply operates the handles and connections for 15 moving the connecting-rod *t* either longitudinally or axially when the movements for changing the speed or direction of movement already described will be effected.

While I have described a construction preferred for effecting the desired results, I am aware that various detail changes may be made without departing from the spirit or scope of the invention, and consequently I do not wish to be limited by positive descriptive terms or expressions hereinbefore employed excepting as the state of the art may require.

Having thus described the invention, what I claim as new is—

30 1. The combination with a motor, a connecting-rod, and a crank having an arm, of a frame having an endless belt arranged therein over suitable pulleys journaled in said frame and a clutch arranged in connection 35 with said arm, adapted to clutch the belt, and impart continuous movement thereto, substantially as set forth.

2. The combination with an endless belt, and pulleys operated thereby, of a reciprocating clutch and means for reciprocating the same, the said reciprocating means being provided with an oscillating arm which is adjustable in its relation to said clutch, whereby the reciprocating movements of said clutch 45 will be increased or diminished in length of stroke, substantially as set forth.

3. The combination with a frame having pulleys and an endless belt arranged on said pulleys, parts of said belt being disposed side by side and movable in opposite directions, a clutch adapted to engage the oppositely-moving portions of the belt alternately, one clutch-dog engaging one portion of the belt at one stroke of the clutch and a second clutch-dog engaging the other portion of the belt in its return stroke, thereby effecting a continuous movement of said belt, substantially as set forth.

4. The combination with a frame having a pair of driving-pulleys disposed side by side in said frame, of an endless belt, arranged in said frame, and over said pulleys and moving in opposite directions on said pulleys to effect an opposite rotation of said pulleys, and a clutch arranged in connection with a sprocket-wheel for driving the wheels of the vehicle, the said clutch being adapted to be brought

into clutching relation to one or the other of said pulleys to effect a reverse movement of the vehicle without changing the direction of movement of the belt, substantially as set forth.

5. In a horseless vehicle, the combination with the body thereof, of a swinging frame movable independent of said body and having means for transmitting power arranged over pulleys therein, means for operating said power-transmitting means and means for transmitting power from said power-transmitting means of the frame to the axle of the vehicle, and means for holding the swinging frame at or near the free swinging end thereof at a definite operative distance from the driven axle, substantially as set forth.

6. In a horseless vehicle, a swinging frame arranged on the body of said vehicle, having therein pulleys and a belt arranged over said pulleys, a clutch for imparting movement to the belt, means for operating the clutch and means for transmitting movement from the pulleys, and a clutch engaging one or another of said pulleys for changing the direction of movement of the last-said transmitting means, substantially as set forth.

7. In a horseless vehicle, a frame arranged on the body of said vehicle and having pulleys therein and an endless belt, arranged over said pulleys, a reciprocating clutch for imparting movement to the belt, and means for reciprocating said clutch, means for transmitting motion from the pulleys including a clutch engaging one or another of said pulleys for changing the direction of movement of the power-transmitting means, substantially as set forth.

8. In a horseless vehicle, a frame arranged on the body of said vehicle and having pulleys therein, and an endless belt arranged over said pulleys, parts of said belt lying side by side and movable in opposite directions, a reciprocating clutch for imparting movement to said belt, said clutch having a pair of clutch-dogs, one dog engaging one of the belt parts and the other dog engaging the other belt part, the said dogs being constructed to enter into operative engagement alternately and means for reciprocating said clutch, substantially as set forth.

9. In a horseless vehicle, a frame arranged on the body of said vehicle and having pulleys therein and an endless belt arranged over said pulleys, parts of said belt lying side by side and movable in opposite directions, a reciprocating clutch for operating said belt and a clutch arranged between a pair of said pulleys in connection with transmitting means, and adapted to enter into clutching relation with one or the other of the pulleys of said pair to effect a reverse movement of the said transmitting means, or to lie idle between said pulleys to effect a stopping of the vehicle, substantially as set forth.

10. In a horseless vehicle, a frame supported by the body and movable in its relation

- thereto and having pulleys therein and an endless belt arranged over said pulleys, a reciprocating clutch for imparting movement to said belt and a clutch interposed between the members of a pair of said pulleys and in connection with means for transmitting power from said pulleys to the axle or wheels of the vehicle, means for operating the last- said clutch to effect a reverse action of parts, and means permitting a movement of the frame upon the body of the vehicle but maintaining the last-mentioned transmitting means in operative relation, substantially as set forth.
11. In a power - transmitting device for horseless vehicles, the combination with a frame, pairs of pulleys and an endless belt arranged thereon, a sprocket or power-transmitting wheel y , a sleeve arranged on the hub of said sprocket-wheel and adapted to enter into clutching engagement with members of a pair of said pulleys, and shifting means, all arranged and operating, substantially as set forth.
12. In a power - transmitting device for horseless carriages the combination with the frame, pairs of pulleys arranged in said frame, an endless belt arranged on said pulleys, a power-transmitting wheel arranged between one of said pairs of pulleys in connection with plates v , v , and a sliding clutching-sleeve arranged on the hub of said power-transmitting wheel and adapted to rotate with said wheel, and a lever having an arm between said plate v , and means for operating the lever to shift said plates and clutching-sleeve, substantially as set forth.
13. In a power - transmitting device, the combination with the frame having power-transmitting pulleys and belt, means for operating said belt, means for varying the speed of the belt, means for transmitting power from the pulleys to the device to be operated and means for reversing the movement of the last-mentioned power-transmitting means, of a single shaft or rod t , for operating both the reversing means and the means for varying the speed of the belt, substantially as set forth.
14. In a power - transmitting device, the combination with the frame having power-transmitting pulleys and an endless belt arranged thereon, a reciprocating clutch, an oscillating arm and a motor for operating said arm, and means for transmitting power from the pulleys, substantially as set forth.

15. In a power - transmitting device, the combination with the frame having power-transmitting pulleys and an endless belt arranged thereon, a reciprocating clutch, an oscillating arm, the clutch being adjustable in its relation to said arm to vary the distance of reciprocation of said clutch and a motor for oscillating said arm, and adjusting means, substantially as set forth.

16. In a power - transmitting device, the combination with the frame having power-transmitting pulleys and an endless belt, a reciprocating clutch having oppositely-disposed clutching-dogs eccentrically pivoted upon a clutch-frame with rollers opposed to said dogs, a reciprocating arm and a motor for driving the same, and means for adjusting the clutch in its relation to the arm, substantially as set forth.

17. In a power - transmitting device, the combination with the body a , having motor e , slotted oscillating arm, and swinging frame, of pairs of pulleys j , j , k , k , and end pulleys m , n , a belt arranged on said pulleys and having parts lying substantially parallel with one another between the pairs of pulleys, a reciprocating clutch with oppositely-disposed dogs engaging said parallel parts of the belt alternately a reciprocating arm, means for swinging the frame and thereby changing the relation of the clutch and arm, substantially as set forth.

18. In a power - transmitting device, the combination with the wheeled and spring-supported body a , having motor e , slotted oscillating arm, and swinging frame connected to said body by a pendulous rod g' , rod g for holding the swinging frame at a definite distance from the axle of the wheels of said body, pulleys and an endless belt arranged on said frame, an oscillating arm pivoted upon bearings on the vehicle-body, a belt-clutch operated by said arm, a motor operating said arm, a shifting clutch, a lever operating the same, a threaded and grooved rod t , operating the shifting clutch and swinging frame, sprocket-wheels f , and g , chains and means for operating said chains, substantially as set forth.

In testimony that I claim the foregoing I have hereunto set my hand this 5th day of May, 1899.

JOHN C. BLEVNEY.
